(57) **CLAIM**

The ornamental design for a display screen with graphical user interface or portion thereof, as shown and described.

DESCRIPTION

FIG. 1 is a front view of an image of a graphical user interface object for a display screen or a portion thereof, according to a first embodiment; and, FIG. 2 is a front view of an image of a graphical user interface object for a display screen or a portion thereof, according to a second embodiment.

The broken lines show portions of a display screen with graphical user interface or portion thereof and form no part of the claimed design. The perimeters of the graphical user interface or portion thereof and the underlying display screen are understood to be flush.
